ABRADING MACHINE

William A. Rosenberger and Walter L. Keefer,
Hagerstown, Md., assignors to Pangborn Corporation,
a corporation of Maryland

Original application May 17, 1934, Serial No. 726,
188. Divided and this application August 29,
1936, Serial No. 98,590

8 Claims.

(Cl. 51—9)

The present invention relates to centrifugal abrading apparatus. More particularly, the present invention is concerned with an abrading machine of the character wherein the abrasive is picked up and directed against the work by sliding the abrasive over blades removably secured to a rotor.

In centrifugal abrading machines of the general character already referred to, the blades wear out rapidly under the action of the abrasive, and must be frequently replaced by new ones, necessitating the stopping of the machine at quite frequent intervals.

It is the primary object of the present invention to construct a centrifugal abrading machine so that the blades may be readily removed and new ones substituted.

A further object of the present invention resides in providing the runner-head of a centrifugal abrading machine with abutment means for positively preventing outward movement of the impeller blades when the machine rotates at high speed.

A still further important object of the present invention resides in providing an improved blade structure having exceptional wearing quality and a rugged attaching portion formed so as to be readily slidably interlocked to the runner head of the rotor.

It is another object of this invention to provide an improved blade structure designed to permit easy assembly therewith of a spring to retain the blades in position after slidable assembly with the runner head.

Another object of this invention resides in providing a centrifugal blasting machine with a runner-head formed to provide undercut grooves through which the abrasive impelling elements may be slid in or out of place thus facilitating rapid changing of the blades.

Further objects of the present invention will become apparent as the detailed description thereof proceeds in connection with the annexed drawings, and from the appended claims.

In the drawing:

Figure 1 is a longitudinal sectional view through the runner-head and casing of the present invention;

Figure 2 is a sectional view taken substantially on the line 2—2 of Figure 1;

Figure 3 is a side elevational view of one of the main impeller blades employed in the device shown in Figure 1;

Figure 4 is a detailed sectional view taken substantially on the line 4—4 of Figure 2.

With continued reference to the drawing wherein like reference characters have been employed to designate like parts throughout the several views thereof, the machine is supported upon a base designated generally at 10. Base 10 may be supported in any desired manner although it preferably is secured to the upper side of a sand blasting cabinet (not shown) in the manner disclosed in the copending application of William A. Rosenberger and Walter L. Keefer, Serial No. 726,188, filed May 17, 1934, of which the present application is a division.

A housing 13 is secured to the lower side of base 10 by means of cap screws 14, and a complementary housing member 15 is secured to base 10 in spaced relation to housing 13 by means of cap screws 16. Housings 13 and 15 house the lower part of an impeller or rotor 17 to be hereinafter described in detail.

An upper housing member 18 is secured to the upper side of base 10 by means of nut and bolt assemblies (not shown) and is provided with a pair of handles (not shown) by which it may be lifted when it is detached from the base. Since the bolt assemblies and handles are described in detail in the above mentioned copending application and form no part of the present invention, a disclosure and description thereof in this application is not necessary. Housing 18 encloses the upper portion of centrifugal impeller or rotor 17 and is preferably provided with a removable wear element which takes the form of a semi-cylindrical ring 21, which may be detachably secured thereto in any suitable manner.

A shaft 25 is mounted for rotation upon base 10, and power may be applied to it in any suitable manner. Shaft 25 is provided with an annular groove 26 and extends through semi-circular recesses 27 and 28 located respectively in housing 18 and base 10. Secured to a reduced portion 29 of shaft 25 by means of a key 31, is a runner-head 32, which supports all of the rotating elements of the blasting machine. Runner-head 32 is provided with an annular flange 33 or equivalent means that cooperates with the impeller blades in a manner to be hereinafter described.

Secured to head 32, as by means of bolt and nut assemblies 34, are a plurality of guide blocks 35 which are provided with inclined faces 36. With particular reference to Figure 4, the neighboring sides of blocks 35 form dove-tail or undercut grooves adapted to retain the abrasive impelling blades.

A plurality of blade members 37 are mounted

upon head 32 and are provided with dove-tailed portions 38 which are disposed within the guide grooves defined by blocks 35. As indicated in Figure 2, blade members 37 are preferably inserted 5 from the center of the assembly and are slid outwardly until they engage flange 33 of head 32, which restrains them from outward displacement in response to centrifugal force. Any suitable means may be employed to restrain blades 37 10 from sliding inwardly under the influence of gravity when the head is at rest, but we preferably employ frictional means which takes the form of flat leaf springs 41, which seat in recesses 42 located in portions 38 of blades 37 and bear 15 against the radial face of head 32. Springs 41, as seen in Figures 1 and 4, bear upon a portion of the surface of runner-head 32 between plates 35. Since springs 41 are retained in recesses 42 the frictional contact thereof with runner-head 20 32 is sufficient to prevent undesirable sliding of blades 37.

Referring more particularly to Figures 2 and 4, blades 37 are provided with substantially flat abrasive-impelling surfaces 43, which extend from 25 the outer ends of the blades to a point near the inner ends thereof. The inner ends of the blades are provided with curved impelling surfaces 44 for a purpose that will presently appear. As seen in Figure 1, the blades decrease in width toward 30 their outer periphery in view of the fact that the velocity of the abrasive increases as it approaches the outer periphery of the blades, and in order to prevent the abrasive from escaping laterally from the blades we preferably provide blades 37 35 with ribs 45, which are co-extensive with their impelling surfaces.

The abrasive may be fed into the center of the blade assembly by any suitable means, but I preferably employ for this purpose the following 40 mechanism, described in detail and claimed in the above mentioned co-pending application.

To this end a stationary and substantially cylindrical abrasive distributing member 51, supported in any suitable manner within the central 45 space 52 formed between the inner ends 53 of blades 37, is provided. Abrasive is supplied to member 51 by means of a cone member 56 secured in place by any suitable means.

Cone 56 receives a spout member 57 through 50 which abrasive is supplied to member 51.

In view of the fact that rotation of head 32 causes blades 37 to function as a centrifugal fan, a high vacuum is developed within the member 51 and spout 57, with the result that any 55 abrasive supplied to spout 57 will be drawn into member 51 and thence through aperture 58 to the blades. We preferably, however, provide head 32 with an auxiliary rotor or fan mechanism 59 for facilitating delivery of the abrasive through 60 aperture 58. Rotor or fan mechanism 59 is secured to shaft 25 by means of a cap screw 61. Mechanism 59 is, preferably, assembled within member 51 in the manner described in co-pending 65 application Serial No. 726,188, wherein the structure of members 51, 56, 57 and 59 is described in detail.

While the present invention is disclosed in connection with the abrasive supply structure of 70 the above mentioned co-pending application, it is to be understood that any other suitable delivery arrangement, such as, a spout delivering abrasive radially into the blades or axially of the axis of head 32 may be used without departing 75 from the spirit of the present invention.

Operation

The work is placed in registry with the discharge opening formed between housing members 13 and 15 and it is preferably mounted on a truck or conveyor or the like so that it may be moved 5 around to expose various areas of it to the blast. Shaft 25 may be rotated at any desired speed, but we find that, with the machine illustrated, a speed of approximately 2400 revolutions per minute, in the direction indicated in Figure 2, is 10 suitable for satisfactory operation of the machine.

Sand or other abrasive is preferably allowed to drop by gravity into spout 57 and it is preferably supplied thereto in uniform quantities as by 15 means of a screw or like conveyor operating at a predetermined constant speed. Rotation of head 32 causes blades 37 to establish a partial vacuum within member 56 and the interior of spout 57, so that the sand entering the spout is picked up 20 by an air stream and enters rotor or fan mechanism 59.

Air and abrasive is accordingly supplied to the annular space defined by member 51 and member 58, and it is uniformly withdrawn from member 51 through aperture 58 by the rotor or fan 25 59 and the suction effect of blades 37.

It should be observed, referring more particularly to Figure 2, that as the abrasive is discharged from aperture 58, it possesses angular as 30 well as radial velocity in view of the impelling action of rotor 59. This initial velocity feature, when taken in connection with the fact that the inner ends of blades 37 are curved, operates to minimize any abrading action as blades 37 pick 35 up the abrasive. In other words, the abrasive discharged from aperture 58 travels outwardly and angularly, and as the angular component of the velocity of an individual particle of abrasive is not greatly lower than the velocity of the 40 inner portions of blades 37 that picks it up, and as these portions of blades 37 are curved, they strike the abrasive a "glancing blow" and wear thereof under such action is minimized.

In view of the fact that the abrasive passing 45 outwardly over blades 37 is increasingly accelerated until it leaves the blades, and it also possesses an angular velocity due to the rotation of the blades, it leaves them at an angle thereto. With reference to Figure 2, the velocity of the 50 abrasive under discharge conditions is diagrammatically illustrated, wherein the radial or outward velocity is represented as V_1 and the instantaneous angular velocity of the sand as it is about to leave the tip of the blade is represented as V_2 . These component velocities, when combined, result in a velocity V_r and approximately represent the conditions existing in the machine during operation. It should be observed that as abrasive is delivered from only a small 55 angular region of the rotor, which in the present case is below the axis of the members and through the openings between the housings 13 and 15, all of the abrasive is utilized for useful work, as no energy whatever is lost by abrasive being thrown 60 against stationary housing 13.

Blades 37, during operation of the abrading machine are thrown outwardly under centrifugal force. This outward movement of blades 37 is, however, arrested when the blades engage flange 70 33. It will, accordingly, be clear that blades 37 cannot be thrown off of runner-head 32 since their radial movement is limited by flange 33 and any axial movement is resisted by the grooves formed between plates 35.

When runner head 32 is stopped the uppermost blades 37, tend to fall or slide toward the axis of the runner-head due to gravity. To prevent this movement of blades 37, which would position the blades so that an undesirable impact of the particular blades with flange 33 would take place, the present invention utilizes springs 41 which frictionally engage runner-head 32. As a consequence when blades 37 are placed in position and slid outwardly against flange 33, they cannot slide inwardly again due to the frictional engagement of the springs 41 and runner-head 32.

When it becomes necessary to replace blades 37, they may be slipped inwardly against the resistance of springs 41 and removed and new blades substituted therefor. Wear element 21 may be readily replaced by removing housing 18.

The invention may be embodied in other specific forms without departing from the spirit or essential characteristics thereof. The present embodiment is therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by United States Letters Patent is:—

1. In an abrading machine, in combination, a disc-like runner-head, a plurality of blades disposed substantially radially with respect to said head, means mounting said blades for guided sliding movement toward and away from the axis of said head, means for limiting outward movement of said blades, and leaf springs engaging a surface of said runner-head and said blades for resisting inward movement of said blades.

2. In an abrading apparatus, in combination, a disc-like runner head having a peripheral, axially extending flange; a plurality of sector-shaped plates, having inclined faces disposed in spaced relation on said disc within said flange, and with their inclined faces disposed to form dove-tail grooves; means for securing said sector plates in place on said disc, and abrasive impeller blades having dove-tail formations thereon slidably connected to said disc through engagement with the walls of said dove-tail grooves, said flange providing an abutment for engaging one end of said blades to retain them against centrifugal force during operation of the abrading apparatus.

3. The construction described in claim 2

wherein said blades are provided with recesses within the confines of said grooves and wherein relatively flat leaf springs are disposed in said recess in engagement with said blades and the surface of said disc exposed between said inclined faces of said sector-shaped plates to restrict free sliding movements of said blade.

4. An impeller blade for use in a centrifugal abrading machine, comprising a body having an abrasive impelling surface, a dove-tail formation on one edge of said body for slidably securing said blade to the rotor of said machine, and spaced shoulders formed by a recess in said dove-tail formation and adapted to retain means therebetween for preventing inadvertent sliding of said blade.

5. In an abrading machine, in combination, a disc-like runner-head, a plurality of blades disposed substantially radially with respect to said runner-head, means mounting said blades for guided sliding movement toward and away from the axis of said head, means for limiting outward movement of said blades, and means for yieldingly resisting inward movement of said blades toward the axis of said head.

6. In an abrading machine, a disc-like runner-head having a substantially flat face and adapted to rotate about an axis normally disposed to said face, a plurality of sector-shaped plates secured to said runner-head in engagement with said face, said plates being spaced from each other and having their neighboring surfaces so shaped as to define a plurality of outwardly extending guideways, a plurality of blades mounted in said guideways for sliding movement toward and away from the axis of rotation of said runner-head, and means for limiting outward movement of said blades in said guideways.

7. The abrading machine described in claim 6, wherein said runner-head is provided with a peripheral, axially directed flange in which said plates nest, and which assists in restraining them against outward movement in response to centrifugal force.

8. In an abrading machine, in combination, a disc-like runner-head, a plurality of blades disposed substantially radially with respect to said head, means mounting said blades for guided sliding movement toward and away from the axis of said head, means for limiting outward movement of said blades, and resilient means engaging a surface of said runner-head and said blades for yieldingly resisting inward movement of said blades.

WM. A. ROSENBERGER.
